US0D1040102S

(12) **United States Design Patent** (10) **Patent No.:** **US D1,040,102 S**
(45) **Date of Patent:** **** Aug. 27, 2024**

(54) **POWER SUPPLY**

(71) Applicant: **Shenzhen Kuake Zhichuang Technology Co., Ltd.**, Shenzhen (CN)

(72) Inventors: **Guocai Wang**, Guangdong (CN); **Yali Shi**, Hubei (CN)

(73) Assignee: **Shenzhen Kuake Zhichuang Technology Co., Ltd.**, Shenzhen (CN)

(**) Term: **15 Years**

(21) Appl. No.: **29/929,094**

(22) Filed: **Feb. 20, 2024**

(51) LOC (14) Cl. **13-02**

(52) U.S. Cl.

USPC **D13/107**

(57) **CLAIM**

The ornamental design for a power supply, as shown and described.

DESCRIPTION

FIG. 1 is a front, left and top perspective view of a power supply, showing our design.

FIG. 2 is a rear, right and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is another rear, right and bottom perspective view of the power supply with the plug folded.

The broken lines depict portions of the power supply that form no part of the claimed design.

1 Claim, 9 Drawing Sheets
